UNITED STATES PATENT OFFICE.

HUGH McDONALD, OF ALLEGHENY, PENNSYLVANIA.

FURNACE-SHIELD.

SPECIFICATION forming part of Letters Patent No. 236,235, dated January 4, 1881.

Application filed April 2, 1880. (No model.)

To all whom it may concern:

Be it known that I, HUGH McDONALD, of Allegheny, county of Allegheny, State of Pennsylvania, have invented or discovered a new and useful Improvement in Furnace-Shields; and I do hereby declare the following to be a full, clear, concise, and exact description thereof, reference being had to the accompanying drawings, making a part of this specification, in which—like letters indicating like parts—

Figure 1 is a side elevation, slightly in perspective, of a puddling or boiling furnace with my improved shield applied thereto; and Fig. 2 is a sectional view through the shield and the door of the puddling-furnace, showing the position of the shield when in use relative to the furnace.

The excessive heat required in the puddling or boiling or reheating or other treatment of iron or steel is such as to be exceedingly oppressive to the workmen, and to interfere materially with the best exercise of skill in doing the work. As a device for guarding against the effects of such high temperature, and to enable the workman to bring out a maximum amount of work in the best condition with the least exposure to himself, shields have been arranged in front of the furnace-door.

My present invention relates to the construction of a shield for such use, and while I have shown it as applied to a puddling or boiling furnace I do not limit myself to the combination of it with any particular kind or class of furnace, but include herein the construction described in its application to any kind or class of furnace where protection to the workman is desired as against excessive heat.

A puddling-furnace of ordinary construction is shown at B. The vertically-movable door D, through which to charge the furnace and remove the product, is of the usual or any known construction. It is provided with the usual stopper or working hole d. Since the workman has to stand opposite the door in charging, working the charge, making up, and removing the ball, protection is chiefly needed at this point. To this end I suspend a movable shield, A, opposite the door, but at a little distance therefrom, as shown in Fig. 2, chiefly in order that the air may circulate

freely in the intermediate space, and lessen to that extent the conduction of heat from the furnace to the shield. This shield is composed of a plate of metal, a, extending over the whole 55 or the greater part of the back of the shield, and a filling, a', of gypsum, plaster-of-paris, lime, or other like material having a low heat-conducting power, and adapted to be applied in a plastic state to the back a, and there 60 hardened or solidified by drying, baking, &c. Any known suitable means may be employed for keeping it in place, such as an inwardly-flanged rim, a², or a series of studs or dowel-pins, a³, either plain or headed. The thickness 65 of this layer need not be very great, but the properties of such materials as non-conductors are so well known in other branches of the art that the skilled workman will have no difficulty in proportioning the thickness according 70 to the amount or degree of protection desired. For ordinary purposes I consider a thickness of about three or four inches sufficient.

This shield is, by preference, made large enough to cover so much of the side of the 75 furnace as comes within the range of the usual positions of the workman in doing his work, and is made with a recess in its lower edge of suitable size and position for uncovering the stopper-hole, as shown, and the flange a² 80 around this recess gives room for the proper manipulation of the workman's tools. It may be made movable in any suitable way, as by being hinged at one edge, or raised and lowered by a lever, or, as the preferable way, it 85 may be hung by straps e and friction-rollers e' on a track-rail, b, which is supported from the furnace-frame by brackets b', so as to be run to one side and out of the way to a position indicated by dotted lines whenever necessary for 90 charging or fixing the furnace, or for removing the ball, the workman for this purpose manipulating the shield by the handles at a⁴.

The structure of shield described may be modified somewhat without any substantial 95 departure from the scope of the present invention, as, for example, an outside plate may be added, as shown by dotted lines at e, Fig. 2, so as to give a hollow box, in which case the non-conducting material may be run in a plastic state or filled in dry, as may be preferred; or, as another modification, a like layer of non-

conducting plastic material may be placed on the back of the plate *a*, as illustrated by dotted lines *e'* of Fig. 2; but in this case the shield should be hung a little farther from the furnace than is represented, in order that the proper air-space may be provided between the two, and here, as before, any suitable plastic having a low heat-conducting power may be employed. The principal object I have in view in the making of a shield in the manner herein described is to utilize for the purpose such materials as can be best employed in a pulverized, broken, or comminuted state; and while the best results may be secured by the use of material having the lowest heat-conducting power, other things being equal, it is still true that advantageous results may follow from the use of materials which are much better conductors of heat than those which I have specifically

named. Hence, by the term "like material," as herein used, I mean a material pulverized, ground, broken, or comminuted; and as to its heat-conducting power, it is only essential that it be so low as to be adapted to operate as a barrier or shield under the circumstances named.

I claim herein as my invention— A furnace-shield consisting of a metal plate lined on one or both sides with plaster-of-paris, lime, or other like material having a low power as a conductor of heat, movably arranged at the side of a furnace opposite the door, and a little distance therefrom, substantially as and for the purposes set forth.

In testimony whereof I have hereunto set my hand.

HUGH McDONALD.
